Des. 234,320
Patented Feb. 11, 1975

234,320

TELEPHONE LIST FINDER

Chuzo Mori, Tokyo, Japan, assignor to Carl Manufacturing Company Ltd., Tokyo, Japan

Filed Feb. 20, 1973, Ser. No. 334,045

Claims priority, application Japan Sept. 8, 1972

Term of patent 14 years

Int. Cl. D19—02

U.S. Cl. D74—1 C

FIG. 1 is a perspective view of a telephone list finder showing my new design;

FIG. 2 is a bottom plan view thereof;

FIG. 3 is a front elevational view thereof;

FIG. 4 is a left end elevational view thereof; and

FIG. 5 is a right end elevational view thereof.

I claim:

The ornamental design for a telephone list finder, substantially as shown.
